UNITED STATES PATENT OFFICE.

HOMER C. LA BATT, OF CHICAGO, ILLINOIS, ASSIGNOR TO WILLIAM J. HERRICK, OF CHICAGO, ILLINOIS.

STOP-REGISTER FOR SHEET-FEEDING MACHINES.

986,726.

Specification of Letters Patent.

Patented Mar. 14, 1911.

Original application filed March 8, 1904, Serial No. 197,083. Divided and this application filed May 31, 1904, Serial No. 210,401. Renewed July 18, 1910. Serial No. 572,584.

To all whom it may concern:

Be it known that I, HOMER C. LA BATT, a citizen of the United States, residing at Chicago, in the county of Cook and State 5 of Illinois, have invented certain new and useful Improvements in Stop-Registers for Sheet-Feeding Machines, of which the following is a specification.

My invention relates to a front register 10 or stop particularly adapted for use with mechanism for transmitting or delivering sheets of paper to a printing press, folding machine, ruling machine or other machine employing or acting upon sheets of paper, 15 and is designed to square or register the sheets before the latter are taken by the grippers or other receiving mechanism of the associated machine to which the sheets are delivered.

20 The invention consists of the combinations, arrangements, and organizations of parts hereinafter particularly described and then pointed out in the appended claims.

In the accompanying drawings, which 25 illustrate one embodiment of my invention,—Figure 1 is a side elevation of a sheet feeding machine shown in connection with the delivery end of a sheet separating machine and the rear end of a printing 30 press, and showing my invention adapted thereto and the connections for operating the same; Fig. 2 is a detail plan view of the front slide block, a portion of the front stop or register and the operative connection between the parts; Fig. 3 is a side elevation of 35 the construction shown in Fig. 2; Fig. 4 is a detail plan view showing the rear slide block to which the rod for communicating motion to the front stop or register is connected, and the actuating cam for retracting 40 the rod to lower the stop into the path of the advancing sheet; Fig. 5 is a side elevation of the construction shown in Fig. 4; Fig. 6 is a plan view of the front end of 45 the feeding machine shown in Fig. 1, illustrating the arrangement and location of the front register or stop; Fig. 7 is a longitudinal sectional view through the delivery end

of the machine; Figs. 8 and 9 relate to details.

This application is a division of an application filed by me March 8, 1904, Serial No. 197,083, and in illustrating the construction and arrangement of the invention herein, I have shown the same adapted to the sheet feeding machine shown and described in the said application. It is to be understood, however, that the invention is not restricted to any particular type or construction of sheet feeding machine, but may be readily 60 adapted to and employed with any other or preferred character of mechanism for transmitting or delivering the sheets to an associated machine employing or acting upon sheets of paper.

The feeding machine with which the present invention is shown associated, may be supported in any suitable manner, as for example as illustrated, and comprises a pair of side rails C, one of which is illustrated in Fig. 1, each side rail being carried by a bracket c bolted to the side member a of a sheet separating machine A. The forward end of each of the rails C is supported by a block c' carried by a bracket c', fastened to the frame of the associated printing press or other machine to which the sheets received from the sheet separating machine A are delivered by the sheet feeding machine. In the construction illustrated the side rails 70 C are so disposed that the forward ends of the same extend under the rear end of the feed board or table b of the printing press and serve to support an extensible section which comprises a pair of side bars D movable through or in guide apertures formed in blocks or boxes d fixed to the side rails C and also through or in aligned apertures in the blocks c'. The bars D are tied together or connected at their rear or free ends 75 by a cross bar d' which is bolted at each end to brackets d', d'', fixed to the ends of the bars D as shown in Fig. 1.

The feeding machine is provided with suitable means for delivering the sheet to 95 the cylinder b' of the printing press or

associated machine. In the present instance such means consist of a series of endless tapes or bands carried by each section. As shown in Fig. 1 the endless tapes c^3 pass over or around the feeding off roll (not shown) of the sheet feeding machine and a roller c^4 , which is mounted on a shaft suitably journaled at its ends in the blocks c' . These tapes c^3 may be spaced apart any suitable distance and carry the sheets to the tapes d^4 of the extensible section, the latter tapes passing around the roller c^4 and at their forward ends over a roller d^5 which is journaled at its ends in the blocks d^2, d^3 . The tapes may be driven in any suitable manner, as through the medium of suitable connections from the sheet separating machine A, and in operation, the tapes c^3 turning the roller c^4 , the tapes d^4 are driven at the same surface speed as the tapes c^3 . From the foregoing it will be understood that as each sheet is delivered to the tapes c^3 , such sheet will be carried and delivered to the tapes d^4 and by them finally delivered to the associated machine. In Fig. 1 the extensible section of the machine is shown in its operative position so as to deliver sheets to the printing press, the usual hinged table section b' of the hand feed board b being swung upwardly out of the way to permit the front edge of the delivery board of the extensible section to occupy the position normally occupied by that of the said hinged section. When it is desired to feed the sheets to the press by hand the extensible section of the feeding machine is retracted and the foldable section b' of the printing press feed board is folded down into operative relation with the press cylinder.

Any suitable means may be provided for advancing and retracting the extensible section of the feeding machine. In the present construction the bars D are made in the form of rack bars, with the teeth of each of which meshes a pinion c^5 , fixed upon a cross shaft c^6 journaled in bearings c^7 depending from the guide boxes or blocks d , as shown in Fig. 1. A hand wheel c^8 is fixed on the shaft c^6 , and by turning such hand wheel the bars D may be advanced or retracted at will, all as more fully shown and described in the application for patent hereinbefore referred to.

Associated with and carried by the feeding machine at its rear end is a registering device which is designed to register or align the front or advancing edge of each sheet. This front register may be of any suitable construction adapted to the attainment of the desired ends. In the present embodiment of the invention it consists of a blade F which is, periodically and automatically lowered into the path of the advancing sheet of paper and is then raised after the front

edge of the paper has been aligned with the edges of the press. This blade in its operative position occupies a vertical position in the path of the paper as clearly shown in Figs. 1 and 7, and is provided at its upper edge with a flange f, which not only serves to strengthen the blade, but also provides means by which the ends of the blade are bolted to a pair of arms f'. These arms are fixed to a rock shaft f², one end of which is journaled in an ear f³ of the support d³, while the other end is journaled in an extension f⁴ of the block d², as seen in Figs. 1, 2 and 3. Fixed to one end of the shaft f² is a crank arm f⁵ to which is jointed one end of a link f⁶, pivoted at the other end to a slide f⁷, moving in a guide or way formed in the block d², as clearly seen in Figs. 2 and 3. Attached to the slide f⁷ is one end of a connecting rod f⁸ extending parallel with the side rail C and connected at its other end to a slide f⁹ mounted and moving in a way formed in the block c', as shown in Figs. 4 and 5. Pivoted to the said block c' is an arm f¹⁰ provided at its upper end with a slot f¹¹ which receives a stud f¹², projecting from the slide f⁹. The arm f¹⁰ is designed to be actuated by a cam, which may take the form of a disk g, having a radical enlargement or cam face g', fixed on a cross shaft g², journaled at the end in the block or box c'. Preferably the arm f¹⁰ is provided with an antifriction roller f¹³ in the plane of movement of the disk g so as to be engaged at the proper time by the cam g' to move the connecting rod f⁸ forwardly and through the medium of the connecting mechanism rock the shaft f² and lower the blade into the path of the advancing sheet as shown in Fig. 7. When the cam portion of the disk passes out of engagement with the antifriction roller f¹³, the blade is raised in any suitable manner, as by means of springs f¹⁴, which are coiled about the rock shaft f², and each of which is anchored at one end to one of the arms f' while the other end is attached to the supports for the shaft, as clearly shown in Fig. 2, so as to normally exert a tendency to elevate the blade F. The shaft g² may be driven in any preferred manner, as through the medium of a shaft g³, and the intermediate gearing shown in dotted lines in Fig. 5, and the shaft g³ has motion communicated to it through the medium of bevel gear g⁴ fixed thereto and which derives motion from the associated machine, such as the printing press or other source. It is to be understood, however, that the arrangement of the connections for driving the various operative parts of the machine is not material and may be varied as desired.

In order to adjust the blade F to the line of the front edge of the sheets, in the event

that such edge should not be cut at an exact right angle to the sides of the sheet, the arms f' may be provided with elongated slots f^{15} as shown in Fig. 7, through which the securing bolts therefor pass. By this arrangement either end of the blade may be moved to adjust the blade to any desired angle.

The sheets of paper pass from the rear 10 end of the tapes d^4 to a delivery device which in the present instance consists of fingers h , which, when the extensible section is in its operative position, occupy the position and take the place of the delivery fingers on the 15 hinged section of the press hand feed board. Each of the fingers h is mounted upon a bracket h' , carried by the cross bar d' , and adjustably secured thereto by means of a set screw h^2 , as seen in Fig. 7. The blade F of 20 the front gage when in active position stands in advance of the ends of the fingers h in the path of the moving sheets so that the sheets passing over the fingers will necessarily engage the blade. In order to prevent the sheets of paper from passing the 25 ends of the fingers h and slipping under the blade, the fingers are provided with spring extensions h^3 fixed to the said fingers and projecting in advance of the latter in such 30 position that the blade F rests thereon when in its depressed position, thereby rendering it impossible for a sheet to slip on the fingers and under the blade and the spring extensions. Two of the spring extensions h^3 are 35 extended sufficiently to project over the press cylinder so as to coact with the press gages which in their depressed position rest upon said extensions as shown in Fig. 7. It is obvious that instead of the fingers h 40 the delivery device may be in the form of a plate extending substantially the width of the machine.

A suitable side register device, adapted to 45 register the side edges of the sheets of paper to place the same in predetermined position for proper alignment with the co-operating part of the associated printing press or other machine, may be employed if desired, and such register may be of the 50 character shown and described in the application hereinbefore referred to or of any other preferred type. Two such side registers S, S' , located at opposite sides of the feeding machine, are indicated, although 55 only one of such registering devices is in operation at a time, the other being adapted to register the same sheets when reversed after being printed on one surface to insure uniformity of impression on opposite 60 surfaces of the sheets. These side registers in the embodiment of the invention illustrated are designed to register the sheets after they have been acted upon by the front stop or register. The stop plate F in its

inoperative position occupies a raised position, as shown in dotted lines in Fig. 3, and as a sheet advances the plate is lowered into its path to square the front edge of the same. The plate is then elevated out of the way of the sheet by the springs f^{14} , as the cam portion g' moves out of engagement with the arm f^{10} , and the sheet is then carried by the tapes to the press gages, which rest at their ends on the spring extensions h^3 of the delivering device and arrest and gage the sheet in the usual manner as when the press is fed by hand. During the period that the sheet is held by the press gages it is registered by the active side register device, and the press gages being then moved out of the 80 way, the sheet is taken by the grippers of the press in the usual manner.

In order to permit the advance and retraction of the extensible section of the feeding machine, the connecting rod f^8 , instead 85 of being permanently fixed to the slide f^9 extends through an apertured lug or ear f^{16} on the said slide and is provided at its end with a shoulder such as the nut f^{17} and at a suitable point at the opposite end of the 90 slide with a nut f^{18} which screws upon a threaded portion f^{19} of the rod as shown in Figs. 4 and 15, thereby detachably connecting the rod to the slide. When it is desired to move the extensible section rearwardly 95 the nut f^{18} is unscrewed, permitting the rod f^{10} to slide through the apertured lug f^{16} on the slide.

Carried by suitable brackets or rods r , which may be bolted at suitable intervals 100 along and transversely to the sections of the frame of the machine, are guides located just over the plane of the tapes c^3 and d^4 to hold the sheets carried by the tapes against the latter and to prevent the sheets from buckling or curling up at the edges. These guides consist of straight rods or wires r' and are designed to be adjusted vertically and laterally in order to coöperate with 105 paper of varying thickness, flexibility and width. To provide for this vertical and lateral adjustment, the guides r' , as shown in Figs. 8 and 9, are carried by vertical arms r^2 which pass through apertures in blocks r^3 provided with set screws r^4 engaging the 110 arms to hold the latter in adjusted position. The blocks r^3 are provided with ears r^5 which engage or embrace the cross rods r and set screws r^6 passing through the ears fix the blocks in any desired position but 115 permit of the blocks being moved along the rods to adjust the guides laterally. The 120 guides r' may be attached to the arms r^2 in any suitable manner. In the present instance I have shown each of the arms provided with a section r^7 between which and the arms r^2 the wires are clamped by thumb nuts r^8 . Any number of the guides desired may 125

be employed, and they may be located directly over the tapes or intermediate of the tapes. When the extensible section is to be advanced or retracted in the manner heretofore described the nuts r^s are loosened so that the guides will slide freely in their supporting arms.

The rear ends of the guides r' of the extensible section preferably extend over the 10 delivery device of the feeder, as shown in Fig. 7. These guides coöperate with the delivery device and form a narrow throat terminating adjacent the plate F and prevent any buckling or curling of the sheets by 15 their impact on the gage.

Having described my invention what I claim as new and desire to secure by Letters Patent is:—

1. In a sheet feeding machine, in combination with the carrying tapes, of a gage located adjacent the delivery ends of the tapes, a rock shaft to which the gage is fixed, a crank arm fixed to the shaft, a slide, a link pivotally connecting the crank arm and the slide, a rod connected to the slide, a cam for moving the rod to rock the shaft in one direction and a spring for rocking the shaft in the opposite direction.

2. In a sheet feeding machine, in combination with the carrying tapes, of a gage blade located adjacent the delivery ends of the tapes, a rock shaft journaled on the frame of the machine, arms fitted to the shaft and carrying the blade, a slide, a 35 crank arm fixed to the shaft, a link connecting the latter arm and the slide, a second slide mounted on the frame, a rod connecting the slides, a shaft journaled on the frame, a cam fixed on the shaft, and an arm 40 pivoted on the frame and engaged by the cam to lower the gage blade into its active position.

3. In a sheet feeding machine, in combination with the moving carrying tapes, a 45 cross bar on the frame of the machine, brackets mounted on and adjustable along the bar, delivery fingers fixed to the brackets substantially in the plane of the carrying surface of the tapes, of the gage associated 50 with the delivery fingers and projecting beyond the ends of the latter when lowered into active position, and means for raising and lowering the gage.

4. In a sheet feeding machine, in combination with the moving carrying tapes, of a 55 delivery device at the rear ends of the tapes and having spring extensions, and a gage adapted to pass the end of the delivery device and engage the extensions 60 when moved to its active position.

5. In a sheet feeding machine, in combination with the moving carrying tapes, a cross bar on the frame of the machine, brackets mounted on and adjustable along

the bar, delivery fingers fixed to the brackets 65 and certain of which are provided with spring extensions, of the gage blade associated with the delivery fingers and adapted to pass across the ends of the delivery fingers and press against the spring extensions 70 when lowered into its active position, means for lowering the blade, and means for raising the blade.

6. In a sheet feeding machine, in combination with carrying tapes and the delivery 75 fingers extending from the rear ends of the tapes and having spring extensions, of a gage blade associated with the delivery fingers and projecting across the ends of the fingers and pressing against the spring extensions 80 when lowered into its operative position, means for raising and lowering the gage, and rigid guide bars located over the tapes and projecting over the fingers and providing with the latter a narrow throat.

7. In combination with a sheet feeding machine having an extensible delivery section provided with carrying tapes, of a front stop carried by the extensible section and comprising a blade movable into and 90 out of the path of the sheets beyond the ends of the tapes of the extensible section, and means for raising and lowering the blade.

8. In combination with a sheet feeding 95 machine having a stationary section and an extensible delivery section provided with carrying tapes, means for advancing and retracting the extensible section, of a front gage carried by the extensible section and. 100 comprising a blade movable into and out of the path of the sheets beyond the end of the tapes of the movable section, a shaft to which the blade is fixed, a slide supported by the stationary section, an operative connection between the slide and the shaft, and means for moving the slide.

9. In combination with a sheet feeding machine having a stationary section and an extensible delivery section provided with 110 carrying tapes, means for advancing and retracting the extensible section, of a front gage carried by the extensible section and comprising a blade movable into and out of the path of the sheets beyond the end of the 115 tapes of the movable section, a rock shaft to which the blade is fixed, a slide mounted on the stationary section, a rod detachably connected to the slide, an operating connection between the rod and the rock shaft, 120 and a cam for moving the slide to lower the blade.

10. In combination with a sheet feeding machine having a stationary and an extensible delivery section provided with carrying 125 tapes, means for advancing and retracting the extensible section, of a front gage carried by the extensible section and com-

prising a blade extending when in operative position beyond the ends of the tapes, a shaft to which the blade is fixed and having a crank arm, a slide, a link pivoted to the slide and the crank arm, a second slide mounted on the stationary section, a rod connecting the slides and detachably connected to one of such slides, a cam for mov-

ing the second slide to lower the blade, and a spring for raising the blade.

In testimony whereof I affix my signature in presence of two witnesses.
